UNITED STATES PATENT OFFICE.

CHARLES THATCHER HATCH, JR., OF ALBION, MICHIGAN, ASSIGNOR TO UNION STEEL
PRODUCTS COMPANY, LTD., OF ALBION, MICHIGAN.

LUGGAGE CARRIER FOR AUTOMOBILES.

Application filed January 8, 1923. Serial No. 611,348.

To all whom it may concern:

Be it known that I, CHARLES THATCHER HATCH, Jr., citizen of the United States, residing at Albion, county of Calhoun, State 5 of Michigan, have invented certain new and useful Improvements in Luggage Carriers for Automobiles, of which the following is a specification.

This invention relates to improvements in 10 luggage carriers for automobiles.

The main object of the invention is to provide an improved collapsible luggage carrier adapted for attachment to the running board of an automobile which may be 15 collapsed upon the running board when not in use.

A further object is to provide an improved collapsible luggage carrier of the class described which is very compact when collapsed, is comparatively light in weight and 20 strong and durable when erected.

Further objects, and objects relating to structural details, will definitely appear from the detailed description to follow.

25 I accomplish the objects of my invention by the devices and means described in the following specification. The invention is clearly defined and pointed out in the claims.

A structure which is a preferred embodiment of my invention is clearly illustrated 30 in the accompanying drawing, forming a part of this application, in which:

Fig. I is an inside elevation of my improved luggage carrier in its collapsed form, 35 its extended position being indicated by dotted lines.

Fig. II is an end elevation, the carrier being shown in erected position upon a support such as the running board of an automobile.

40 Fig. III is an enlarged fragmentary detail end elevation, the carrier being shown in erected position by full lines and in collapsed position by dotted lines.

Fig. IV is a fragmentary end elevation 45 showing an article, indicated by dotted lines, being strapped to the carrier.

In the drawings similar reference characters refer to similar parts throughout the 50 several views.

Referring to the drawings, I provide a pair of uprights 1 which are of channel cross section and disposed with their channels facing outwardly. The supporting 55 clamps 2 are of a character adapted to be

engaged with the running board of an automobile, as 3. These clamps have upwardly projecting spaced ears 4 between which the hinge members 5 are pivoted. These hinge members have shank portions 60 disposed in the channels of the uprights and secured thereto by the pivots 6. The uprights have longitudinal slots 7 at their upper ends.

I provide a lazy tongs structure made up 65 of a plurality of bars 8 which are connected at their crossing points, as 9, and at their ends, as at 10. The upwardly directed outer or end bars 11 have outwardly curved upper ends 12 provided with curved slots 13. The 70 lower ends of the downwardly directed end or outer bars are pivoted at 14 to the brackets 15 projecting inwardly from the lower ends of the uprights. Slides 16 are secured to the uprights by means of the pins 17 75 engaging the slots 7. These slides carry pins 18 which engage the slots 13 in the bars 11. This arrangement makes it possible to use relatively short uprights, thereby permitting the structure to be folded when extended 80 upon the running board of an average width.

I also preferably provide an intermediate clamp 2' to which one of the intermediate bars is connected by the hinge member 19. This provides a very secure support for 85 the carrier upon the running board and at the same time permits its being collapsed, as stated.

If desired, the article to be carried, as 90 indicated at 20, may be secured to the uprights by a strap 21 arranged through the slots 7. The uprights are preferably provided with arms 22 which are pivoted thereto at 23 to be collapsed against the inner side of the arms or to be extended to a 95 horizontal position, as indicated by dotted lines in Fig. II.

These arms collapse within the plane of the uprights and do not in anywise interfere with the structure being collapsed flat 100 upon the running board.

My improved carrier is simple and economical in its parts and at the same time is very strong and rigid.

Having thus described my invention, what 105 I claim as new and desire to secure by Letters Patent, is:

1. In a folding luggage carrier, the combination with clamps adapted to be engaged with the running board of an automobile, 110

uprights of channel cross section mounted on said clamps, said uprights being arranged with their channels facing outwardly and having longitudinal slots at their upper ends, a plurality of bars disposed and pivotally connected to provide a lazy tongs structure, the upper ends of the upwardly projecting end bars being outwardly curved and having curved slots therein, inwardly projecting brackets disposed at the lower ends of the uprights and provided with pins engaging the lower ends of the downwardly projecting end bars, and inwardly projecting slides slidably engaging said slots in said uprights and provided with pins engaging said curved slots in the upper ends of said end bars.

2. In a folding luggage carrier, the combination with clamps adapted to be engaged with the running board of an automobile, uprights having longitudinal slots at their upper ends, a plurality of bars disposed and pivotally connected to provide a lazy tongs structure, the upper ends of the upwardly projecting end bars being outwardly curved and having curved slots therein, inwardly projecting brackets disposed at the lower ends of the uprights and provided with pins engaging the lower ends of the downward-

ly projecting end bars, and inwardly projecting slides slidably engaging said slots in said uprights and provided with pins engaging said curved slots in the upper ends of said end bars, said uprights being pivotally mounted on said clamps so that the carrier may be collapsed upon the running board upon which the carrier is mounted.

3. In a folding luggage carrier, the combination with clamps adapted to be engaged with the running board of an automobile, uprights having longitudinal slots at their upper ends, a plurality of bars disposed and pivotally connected to provide a lazy tongs structure, the upper ends of the upwardly projecting end bars being outwardly curved and having curved slots therein, inwardly projecting brackets disposed at the lower ends of the uprights and provided with pins engaging the lower ends of the downwardly projecting end bars, and inwardly projecting slides slidably engaging said slots in said uprights and provided with pins engaging said curved slots in the upper ends of said end bars.

In witness whereof, I have hereunto set my hand and seal.

CHARLES THATCHER HATCH, Jr. [L.S.]
